UNITED STATES PATENT OFFICE.

AUGUST H. GUSSMAN, OF HACKENSACK, NEW JERSEY.

LUBRICATING APPARATUS.

Application filed July 9, 1925. Serial No. 42,410.

Among the principal objects which the present invention has in view are: to lubricate the pistons and cylinders of an internal combustion engine during periods when 5 the engine is operating slowly; to supplement the usual splash system of lubricating internal combustion engine cylinders for lubricating the same during the periods of inactivity of said splash system and when the 10 engine is running; to provide means for discontinuing the operation of said supplemental means as and when the speed of the engine is increased; and to simplify and cheapen the construction.

15 The drawing is a side elevation of an engine of the character mentioned equipped with a lubricating system, constructed and arranged in accordance with the present invention, the view being shown partly in section for disclosing the interior constructions of parts thereof.

Description.

Referring to the drawing the pistons 5 and the cylinders 6 are of the usual automobile engine construction. The said cylinders are made in blocks and the pistons are operatively connected with the cranks 7 of the shaft 8 by connecting rods 9. Each of 30 the rods 9 are provided with splash buckets 10 which dip into the oil carried in the crank case 11 and in the course of operation of the crank with which it is connected, throw the contents of the bucket upward into the cylinder 6 just above and at the moment when the piston is in its elevated position. This 35 construction is well known as the splash system for lubrication.

The system depends for casting the oil 40 from the buckets 10, on the speed of the engine. It is obvious that if the engine is turning slowly there is not enough speed in the crank with which each of the connecting rods 9 are connected to throw the oil or other lubricant upward into the cylinder. Experience has shown that many 45 cylinders of automobile engines become scored or carbonized by the heating during the period known as idling or when starting the engine by means of a self starter. When an engine is stopped and permitted to cool, the lubricant on the walls of the cylinders is evaporated or burned by the residual heat in the cylinders, therefore, when 50 the engine is started, the piston is compelled to move over a dried surface, which calls for

greater outlay of power in the starting mechanism and endangers the walls of the cylinders if any burnt product has been left in the combustion chamber thereof. To 60 avoid this, I have provided a supplemental oiling system having an oil pump 12 which is connected with the intake pipe 13 and the delivery pipe 14. The intake pipe 13 opens into the crank case 11 to take the oil 65 therefrom for supplying the pump 12. A delivery pipe 14 is connected with the manifold 15 which has a series of spraying nozzles 16 by which the lubricant delivered by the pipe 14 and manifold 15 is squirted into the 70 cylinders 6.

To operate the pump 12 at a high rate of speed when the engine is running slowly, the pump shaft 17 and the driving shaft 18 when operatively connected, are provided 75 with and driven by a pinion 19, the teeth of which mesh with the toothed ring 20 on the fly-wheel 21 of the automobile. The difference in diameter between the pinion 19 and the ring 20 insures a relatively high 80 rate of revolution of the propeller shaft 18.

The shaft 18 has mounted thereon a bevel gear wheel 23, the teeth of which are meshed with the teeth of a corresponding bevel gear wheel 24. The wheel 24 is suitably mounted 85 in a frame and disposed in perpendicular relation to the wheel 23. The center of the hub of the wheel 24 is perforated to pass a thrust rod 25 which is supported by the long arm of a bell crank lever 26. The short arm 90 27 of the bell crank 26 is bifurcated with rounded heads to engage the end flanges of a thrust collar 28, permanently engaged therewith is a truncated clutch member 29.

The member 29, has corelation with the 95 member 30 which is mounted permanently on the propeller shaft 18.

Permanently mounted in an extension of the hub of the wheel 24 are bell crank levers 31, the ends of each of which rest 100 above to engage the thrust pin 25, whenever the bell cranks 31 are rocked by the centrifugal effect of the weighted balls 32.

The thrust rod 25 is depressed correspondingly moving the lever 26 to rock the same 105 on its pivot to remove the clutch member 29 from engagement with the clutch member 30. This condition continues while the engine is running above a predetermined speed. When, however, the engine speed is 110 reduced below such predetermined point, the weighted balls 32 lift the levers 31 from the

rod 25 and permit the pull spring 22 to rock the lever 26 to re-engage the clutch member 29 with the clutch member 30. This arrangement immediately starts operating the pump in the oil chamber 12 with the result that spraying of the oil from the nozzles 16 is resumed, with the result that with the diminution of the lubricating effect of the splash system the auxiliary or spraying effect is augmented. In this manner the cylinders 6 are at all times lubricated.

While I have herein described the lubricating apparatus as employing an oil circulating pump and piping therefor, it will be understood that other forms of power units may be employed such as for instance an air pump which would deliver air through the nozzles 16, said nozzles being disposed below the level of the oil in the crank case 11. Many well known power units could be used for spraying the oil against the wall of the cylinders, all of which I consider as coming within the scope of the present invention.

25

Claims.

1. A lubricating apparatus comprising an auxiliary power apparatus for spraying oil on the walls of the cylinders of an internal combustion engine; and means for operatively connecting said apparatus and said engine when the latter is operating below a predetermined speed, said means embody-

ing a speed controlled clutch driven by said engine and adapted to operatively connect 35 said engine and said power apparatus when said engine is operating below a predetermined rate of speed.

2. A lubricating apparatus comprising a series of spray members, each of which is 40 disposed below one of the cylinders of a multi-cylinder internal combustion engine; an oil pump operatively connected with the oil supply of said engine and with said spray members; and a releasable connecting mechanism for operatively connecting said spray members and pump when the running of said engine is below a certain predetermined point.

3. A lubricating apparatus comprising a 50 series of spraying members disposed in the crank case of a multi-cylinder engine, one of said members being in line with each of the cylinders of said engine; a driving shaft operatively connected with said pump and with the driving shaft of said engine; a releasing mechanism for releasing said pump from said driving shaft, said mechanism comprising a releasing clutch and a centrifuge mechanism operatively connected with 60 said driving shaft, said centrifuge mechanism being arranged to release said clutch when the speed of said driving shaft is above a predetermined rate.

AUGUST H. GUSSMAN.
